DENTAL DRILL HANDPIECE

Marius J. Morin, 4610 Sepulveda Blvd.,
Torrance, Calif. 90505

Filed Oct. 29, 1975, Ser. No. 626,748

Term of patent 14 years

Int. Cl. D24—02

U.S. Cl. D24—1 D

FIG. 1 is a side elevation view of a dental drill handpiece, the opposite side being the mirror image thereof;

FIG. 2 is a top plan view thereof;

FIG. 3 is a bottom plan view thereof;

FIG. 4 is an enlarged end elevation view thereof, as seen from the left end of FIG. 1;

FIG. 5 is an enlarged end elevation view thereof, as seen from the right end of FIG. 1;

FIG. 6 is a partial view taken along line 6—6 of FIG. 1; and

FIG. 7 is a partial view taken along line 7—7 of FIG. 1. I claim:

The ornamental design for a dental drill handpiece, substantially as shown and described.
